UNITED STATES PATENT OFFICE.

WILLIAM H. OPITZ, OF BEAVER, PENNSYLVANIA, ASSIGNEE, BY MESNE ASSIGNMENTS, TO THE WAYNE PUMP COMPANY, OF BALTIMORE, MARYLAND, A CORPORATION OF MARYLAND.

OIL PUMP.

Application filed June 20, 1927. Serial No. 199,899.

This invention relates to improvements in pumps, such as oil pumps or the like, and especially in the type of pumps which have an outlet nozzle and a cooperating drain pipe 5 movable into and out of receiving position with said nozzle, for the purpose of catching the remaining drops which drain from the nozzle after use and returning said oil to the containing receptacle. My invention relates particularly to an improved type of 10 nozzle and drain pipe in which advantages are realized heretofore unknown.

One of the objections encountered in devices heretofore employed, has been that 15 the movable drain pipe coming into a receiving position relative to the nozzle, contacts drops of oil or other dispensed liquid hanging from the end thereof, which oil runs down the outer surface of the drain 20 pipe. When it is attempted to increase the clearance between the end of the drain pipe and the nozzle to prevent this, the drain pipe is subject to having moisture from rain and dirt find its way into its opening, which 25 is detrimental to the oil or liquid contained in the pump.

Another objection found in devices heretofore employed, has been that leakage occurs 30 between the cap and the pipe of the drain pipe which is caused by oil or other liquid being thrown to the walls of the pipe when the pumping commences, particularly in cases where air is contained in the pipes and a sputtering and spitting action is had when 35 pumping starts.

The principle objects of my invention are 40 to provide an improved nozzle and drain pipe in pumps of the general character described above, which are free from the above objections, and which embody certain improved structural features hereinafter more clearly pointed out.

These and other objects are accomplished 45 by means of the arrangement disclosed in the accompanying sheet of drawing, in which—

Figure 1 is a side elevation of a pump embodying a nozzle and a movable drain pipe 50 constructed in accordance with my invention;

Figure 2 is an enlarged cross-sectional view of the end of the drain pipe and the cooperating nozzle constructed in accordance with my invention;

Figure 3 is a cross-sectional view taken on

the line 3—3 of Figure 2 looking in the direction of the arrows;

Figure 4 is a view of the bottom end of the nozzle and skirt, constructed as shown in Figure 2;

Figure 5 is a view similar to Figure 2 of a modified form of my invention; and

Figure 6 is a cross-sectional view taken on the line 6—6 of Figure 5 and looking in the direction of the arrows.

The various novel features of the invention will be apparent from the following description and drawings and will be particularly pointed out in the appended claims.

Referring to the drawing, it will be noted 70 that my invention is illustrated, applied to a pump designated generally 10, having a pump cylinder 11, and a handle 12 mounted on a container 13 shown in a fragmentary manner in Figure 1. Mounted on the opposite end of the pump is an outlet nozzle 14 having an outlet pipe 15 and a protective skirt 16 over-hanging the outlet nozzle. At the lower end of the pump is an off-set pipe 17 containing at its upper end a bearing 75 and a torsional spring not shown, but which constitutes means by which the S-shaped pipe 18 may be rotated in its seat in the upper end of the pipe 17 and resiliently held by the spring in such a manner that it 80 is normally positioned in receiving alignment with the end of the nozzle 15. Pumps of this general character are old and well known in the art, and it is understood in operation that when it is desired to dispense 85 liquid from the pump, that the pipe 18 is merely engaged manually and is thrust in a direction away from the end of the nozzle against the opposition of the spring, an extent sufficient to permit a receiving container to 90 be placed under the nozzle. When sufficient liquid is dispensed the operator merely removes the receiving container and permits the pipe 18 to resume its normal position which 95 is in receiving alignment with the nozzle, this action taking place under the influence of the spring which turns the pipe 18 in its bearing mounting.

Referring particularly to Figure 2, it will be noted that the skirt 16 is provided with a 105 cut-away opening 19 and at a point diametrically opposite inwardly of the outer circumference, has a depending lug 20. The drain pipe in the structure shown in Figure 2 comprises a pipe such as the pipe 18, having a cap 110

21 mounted on the upper end thereof, and held by any suitable means such as the screw 22. The cap has an opening 23 through its upper end in which is positioned a sleeve 24 having its lower end depending therefrom and positioned within the sleeve 18 in a manner to project a considerable distance below and cover the jointure between the cap and the pipe. The upper end of the pipe 24 projects beyond the cap as at 25 and has provided at one side thereof, a cut-away portion 26.

Attention is directed to the fact that the opening 19, and the skirt 16, the depending lug 20 on the skirt and the opening 26 in the sleeve 24 are all positioned in a line which coincides with the path of movement of the drain pipe 18 when it is moved out of and into cooperative relationship with the nozzle. These features are clearly shown with reference to Figure 3.

In Figure 5, I have shown a modified form of my invention, many features of which, however, are similar to those of the form shown in Figure 2 and the parts which are similar bear similar reference characters. The difference resides primarily in the fact that the upper end of the cap 27 is positioned flush with the end of the nozzle 15 instead of projecting slightly above as in the case of the other form. Also, the portion of the drain pipe structure which cooperates with the nozzle is the upper projecting sleeve 28 of the cap 27 itself, rather than an inserted sleeve 24, as disclosed in the other figure. In this modification, a sleeve 29 is provided seated tightly within the opening in the cap and having sufficient length to cause it to project into a pipe 18' sufficiently to amply cover the jointure between the pipe and the cap.

The advantages of my improved invention are manifest when the structures are fully understood, attention being directed to the fact that sleeves 24 and 29 in the two forms prevent any oil that may be thrown onto the internal walls of the sleeve and cap, from leaking between the cap and the pipe and thence down the outside of the drain pipe 18. In addition, the provision for a cut-away portion 26 and 26' in the two modifications eliminates the objection of oil being scraped off of the end of the nozzle by the upper outside edge of the drain pipe in its movement into a receiving position, and oil running down the outside of the drain pipe as a result thereof. In addition to the elimination of these objections, the lug 20 pending from the skirt portion, whereby moisture and dirt are prevented from being blown or finding their way into the drain pipe 18. Attention is directed to the fact, that the lug 20 has another valuable function, in that it forms a stop for the moving drain pipe, acting to arrest the drain pipe in such position, that the nozzle and drain pipe are in alignment and the nozzle is held free from contact with the walls of the drain

pipe. This is clearly illustrated in Figures 3 and 6, and makes a great improvement in that it eliminates the necessity of using the end of the nozzle as a stop for the moving drain pipe which function would be apt to result in damage to the nozzle, and it further assures that all lubricant or other dispensed liquid collected by gravity on the end of the nozzle, will be directed down the drain pipe 18 free from the walls and without contacting the upper end of the pipe with the undesirable result of having lubricant on the outside thereof.

The opening 19 in the skirt permits the movement of the drain pipe into its receiving position with the provision of, throughout a considerable circumference, a skirt of increased length which further protects the openings 26 and 26', and the upper end of the receiving pipe.

It is to be understood that my invention is applicable to any device where the same problems of draining fluids are encountered.

I claim:

1. In a pump, the combination of a relatively movable nozzle and a drain pipe, said drain pipe comprising a pipe, a cap and a sleeve positioned in said pipe and cap, and covering the jointure therebetween, said sleeve extending beyond said cap and having a cut-away portion adapted to underly said nozzle, in its path of movement into and out of cooperation with said drain pipe.

2. A pump, a relatively movable nozzle and drain pipe, a cap fitting on the end of said drain pipe and a sleeve positioned in said cap having a portion projecting beyond the jointure between said cap and pipe.

3. In a pump a relatively movable nozzle and drain pipe, a cap fitting on the end of said drain pipe having an opening therethrough, a sleeve tightly fitted in said opening, said sleeve extending into said pipe and covering the jointure of the said pipe and cap.

4. In a pump a relatively movable nozzle and drain pipe, a cap fitting on the end of said drain pipe and a sleeve positioned in said cap having a portion projecting beyond the jointure between said end cap, said sleeve being extended in the opposite direction beyond said cap to provide a portion adapted to cooperate with said nozzle.

5. In a pump a relatively movable nozzle and drain pipe, a cap mounted on said drain pipe and means positioned in said cap and pipe to cover the jointure therebetween.

6. In a pump, a relatively movable nozzle and drain pipe, a cap having a perforated end portion and a skirt portion and a sleeve fitting in said perforated end portion of said cap and extending in a manner spaced from and concentric with said skirt portion, said cap and sleeve being mounted on said drain pipe with the end of said drain pipe located in the space provided between said sleeve and skirt.

7. In a pump a relatively movable nozzle and drain pipe, a cap positioned on the end of said drain pipe, a sleeve tightly fitting an internal opening of said cap and having a portion projecting beyond the jointure of said pipe and cap; said sleeve also projecting in the opposite direction beyond the end of said
- 5 cap, said last named projection having a cut-away portion to provide an increased amount of clearance between said sleeve and 10 said nozzle.

Signed at Beaver, Pennsylvania, this 14th day of June, 1927.

WILLIAM H. OPITZ.
